KNITTING MACHINE PATTERN MECHANISM

Paul W. Bristow, Laconia, N. H., assignor to Scott & Williams, Incorporated, Laconia, N. H., a corporation of Massachusetts

Application April 21, 1947, Serial No. 742,905

5 Claims. (Cl. 66—50)

1

This invention relates to a knitting machine and has particular reference to the control of a pattern mechanism, specifically of a pattern mechanism designed to operate through a number of cycles in the formation of a single stocking.

This application is in part a continuation of my application, Serial No. 635,644, filed December 18, 1945. One of the forms of the invention disclosed herein has also been illustrated in the application of Lawson and Bristow, Serial No. 728,226, filed February 13, 1947.

The general object of the present invention is the provision of a pattern mechanism control of special characteristics which will become apparent hereafter involving, in particular, the interruption of advance of the pattern mechanism during the formation of heels of stockings and the retiming of the pattern mechanism in order to insure the proper relationship of the pattern to each stocking knit under its control. The foregoing broad object of the invention as well as other objects relating particularly to details of construction and operation will become apparent from the following description read in conjunction with the accompanying drawings, in which:

Figure 1 is a horizontal section showing the major portions of the pattern mechanism and its controls;

Figure 2 is a perspective view showing a needle jack and cams for selecting the same;

Figure 3 is a fragmentary elevation of the pattern mechanism and its controlling device;

Figure 4 is a perspective view of the same;

Figure 5 is a fragmentary elevation of the same;

Figures 6 and 7 are elevations of controlling cams for the needle selecting means;

Figure 8 is a plan view of an alternative form of pattern device embodying the principles of the invention, certain parts being in section;

Figure 9 is a fragmentary sectional view showing various elements of the trick wheel advancing means of Figure 8;

Figure 10 is a view partly in elevation and partly in section showing the device of Figure 8; and

Figure 11 is an approximately radial section showing the same device associated with a lower needle cylinder of a superposed cylinder machine.

My prior application, Serial No. 635,644 referred to above, discloses a knitting machine of the superposed cylinder type in which double ended needles may selectively knit in the upper

2

and lower cylinders for the formation of reversely concatenated loops. Lower and upper sliders control the needle movements when they are in the lower and upper cylinders, respectively, and for the purpose of needle selection the lower sliders are subject to control of a trick wheel which, together with its controlling devices, constitutes the subject-matter of the present application. It will be evident that the invention is of more general application for the direct control of needles or for the control of sliders, jacks or other independently movable elements of a knitting machine. In the present application the control of sliders and jacks will be referred to specifically for the explanatory purposes. Only so much of the knitting machines are disclosed as are necessary to the understanding of the present invention and for additional components of these knitting machines reference may be made to the co-pending applications above mentioned. Reference will be first made to Figures 1 to 7, inclusive, which disclose an embodiment of the invention incorporated in the machine of my application, Serial No. 635,644. The lower sliders are controlled in this machine to provide selective needle movements, these sliders being indicated at 2 and being provided with saw-tooth butts 4.

To serve for the control of the lower sliders 2 by action upon their butts 4 there are provided cams 6 mounted in a guiding member 8 for radial sliding movement with respect to the lower cylinder. Each of these cams is provided with a notch 10 at its outer end engageable by an individual lever 12 of a stacked group, which levers are provided with follower ends 14 engageable with the butts of elements 16 mounted in a trick wheel 18, springs 20 serving to urge the levers 12 in a clockwise direction, as viewed in Figure 1. An upwardly projecting member 22 carried by a lever 24 urged clockwise, as viewed in Figure 1, by a spring 26 serves, under proper conditions, to move all of the levers 12 counterclockwise to withdraw the cams 6 outwardly irrespective of the butts of elements 16 which may be operatively related to their ends 14.

The trick wheel 18 carries a ratchet 28 arranged to be acted upon by a pawl in the form of a bar 30 having a hooked end. This bar 30 is pivoted at 32 to a lever 34 secured to a vertical shaft 36 which carries an arm 38 arranged to be acted upon by an adjustable screw 40 carried by one arm of a bell crank 42 pivoted at 44 and having its other arm provided with a follower roller 46 arranged to be acted upon by cam 48 rotating with the upper needle cylinder. By

the action of this cam 48 and the connections just described, the trick wheel is advanced one step upon each rotation of the needle cylinders. A spring 50 urges the lever 34 clockwise, as viewed in Figure 1, while a light spring 52 acting on the bell crank 42 prevents disengagement of the screw 40 from the arm 38.

Overlying the pawl bar 30 is a lever 53 having a laterally extending end 54 provided with a notch 56 in which is receivable a pin 58 carried by a lever 60 pivoted coaxially with the levers 12 and having a follower end 62 arranged to be acted upon by butts 64 at one level in the trick wheel. The series of butts 64 are continuous about the trick wheel except for one break provided for the purpose of timing. A Bowden wire 66 connects the lever 60 to a push rod 68 arranged to be acted upon at proper times, through the lever 69, by cams 70, 72 and 74, carried by the main cam drum 76. (See Figure 7.)

The lever 53 is pivoted at 32 to the lever 34 and is provided with a slot 55 embracing a stud 57 threaded in the bar 30. A spring 59 connected between the end 54 and the bar 30 normally urges the lever 53 counterclockwise relative to the bar 30, as viewed in Figure 2, to a limit position in which the stud 57 is in engagement with the right hand end of the slot 55. During normal operation, the lever 53 may be regarded as integral with the bar 30.

A Bowden wire 78 connects the lever 24 with a push rod 80 which is arranged to be acted upon, through the lever 81, by cams 82 and 84 on the cam drum 76. (See Figure 6.)

During the formation of a leg of a stocking, preceding which action the trick wheel is stationary in retimed position achieved in the fashion hereafter described, the cams 6 are controlled by the trick wheel, the pin 58 on the lever 60 being in alignment with the notch 56 so that the pawl bar 30 is active for the purpose of advancing the trick wheel step by step on each rotation of the cylinders. By the selective action of the cams 6 on the butts 4, some of which butts are removed in the usual fashion to provide the proper selections, the needles controlled by the sliders are selectively raised to be differentiated from each other for any desired purpose, as, for example, to receive selectively wrap yarns in accordance with the disclosure of my application, Serial No. 635,644.

During the formation of the leg, the cam 70 acts to pull the lever 60 to the full line position illustrated in Figure 1 through the Bowden wire 66 so that, pin 58 being aligned with the notch 56, the pawl bar 30 will have full racking strokes. Lever 24 is released by its Bowden wire 78 since the lever 81 which actuates plunger 80 now rides on the surface of drum 76.

During the formation of the heel, in order not to interrupt the continuity of the wrap patterns extending from the front of the leg into the instep, the trick wheel is stopped from rotation, while at the same time the cams 6 are drawn outwardly so as not to engage the saw-tooth butts of the lower sliders. The former action occurs through the action of cam 72 and plunger 88 on the Bowden wire 66, which rocks the pin 58 to the right as viewed in Figure 1 to bring it out of alignment with the notch 56 in the laterally extending end 54 of the lever 53. Even though the cam 48 continues to rock the shaft 38, the pawl is held in a retracted position so that it cannot move forwardly to engage the

next ratchet tooth. In order to render cams 6 inactive, the lever 24 is rocked by the action of a cam 84 on plunger 80 through the Bowden wire 78 so as to cause the upturned portion 22 of the lever 24 to engage levers 12 to pull the cams outwardly.

During the formation of the foot, cam 74 aligns pin 58 with notch 56 so that normal racking of the trick wheel continues. Cams 6 are again rendered active by release of lever 24 following passing of cam 84 beyond the follower lever controlling plunger 80.

In the formation of the toe, narrowing and widening are carried out as described above for the heel. During the formation of the toe, however, it is desirable to cause retiming of the trick wheel to set it for the beginning of the next stocking. For this purpose, while the cams 6 are again rendered inactive by the rocking of the lever 24, through the action of cam 82, the lever 60 is released by its Bowden wire 66 (by the dropping of the cam follower lever of plunger 68 off cam 74) so that, if not otherwise prevented, it could move to the left-hand dotted line position illustrated in Figure 1, so that again the pawl 30 would be rendered inoperative. This, however, is prevented by the presence of butts acting on the follower end 62 of the lever until the trick wheel turns to present to the follower a trick having a butt missing at the level of the follower end 62. At such time the pin 58 will rock to the left and, accordingly, further advance of the trick wheel will cease. The conditions so attained then prevail until the knitting of the leg of a subsequent stocking is started.

Coincidently with the beginning of the formation of the leg, the cam 70 acts to pull the lever 60 to the full line position of Figure 1.

The purpose of connecting lever 53 yieldingly to bar 30, rather than making end 54 integral with bar 30, is merely to prevent jamming when racking the main cam drum by hand, which jamming might occur if roller 46 was not on cam 48. In view of the yielding connection, lever 60 may be rocked by its Bowden wire even though its pin 58 is engaged in notch 56.

Figures 8 to 11, inclusive, disclose a modified mechanism embodying the invention which has been disclosed in the Lawson and Bristow application referred to above and resembles, in its basic principles, the pattern mechanism illustrated in the patent to Lawson, 2,411,795, dated November 26, 1946. In the case of this modification, the pattern mechanism controls jacks 150 provided with saw teeth and arranged to slide and also tilt in slots 154 provided in a lower needle cylinder 152 of a superposed cylinder type of machine. Through these jacks, needles are controlled for various purposes as disclosed more fully in said Lawson and Bristow application.

For the control of the saw-tooth jacks there are provided a series of cams, one for each level of the saw-tooth butts. These cams take the form of stacked slides 160 tilted to the horizontal as indicated particularly in Figure 10. Each of these slides is provided with a cam portion 162 which actually engages the jacks. The slides are urged inwardly toward the needle cylinder by engagement of springs 168 and 170 with projections 164 and 166 on the slides. In view of the close arrangement of the slides the projections 164 are provided on alternate slides while the projections 166 are provided on intermediate

slides. The springs 168 and 170 take the form of comb-like members, the prongs of which individually engage the projections. The slides are additionally provided with butts 172 which may be selectively broken away. These butts are engageable by three fingers 174 carried by upright shafts controlled from the main pattern drum of the machine so that groups of the slides may be selectively drawn out of action away from the needle cylinder.

Each of the slides is provided with a projection 176, which projections are arranged to be acted upon by the butts on the tricks 178 carried by the trick wheel 179. During the formation of the portions of a stocking in which patterning occurs the trick wheel is advanced in the formation of every course by a mechanism which will be recognized to be that of said Lawson patent. The trick wheel is secured to a gear 180. A cam 182 rotating with the needle cylinders acts upon each rotation of the cylinders upon a follower roller 184 carried by a triple arm lever 186 pivoted at 188 to the frame of the machine. The intermediate arm 189 of this lever is provided with a hardened pad 190 which acts upon an adjustable follower screw 192 carried by an arm 194 of a yoke 195 pivoted on a pin 198 carried by the machine frame. An adjustable screw 200 carried by arm 194 engages a portion of the frame to limit counterclockwise motion of the arm 194 which is urged in a counterclockwise direction as viewed in Figure 8 by a spring 196. A second arm 202 of the yoke 195 carries on a pivot 204 a lever 206 which, at one end, is provided with a gear segment 208. This same end of the lever 206 is adapted to engage an eccentric stop 210 which is secured in adjusted position by a screw 212. The other end of the lever 206 carries an adjustable screw 214 which is arranged to engage a lug 215 carried by the arm 202.

The operation of the mechanism just described in advancing the trick wheel will be clear considering as a starting position the location of the parts illustrated in Figure 8. As the lever 186 is moved counterclockwise by the cam 182 the yoke 195 is moved clockwise with the result that the teeth of the segment 208 engaged the teeth of the trick wheel gear 180. The pivot 204 is provided with sufficient friction, for example, by means of friction washers, so that the lever 206 and the arm 202 move as a unit in this operation. As the clockwise movement on the shaft 198 continues, the angular relationship between the lever 206 and the arm 202 changes so that the segment 208 advances the gear 180. This action continues until the stop screw 214 engages the lug 215 which should coincide, substantially, with the limit of movement of the lever 186 under the action of cam 182. The cam 182 then releases the lever 186 and the spring 196 produces a movement counterclockwise of the yoke 195. The lever 186 is rocked clockwise by this action, a light spring 181 serving to maintain engagement between the pad 190 and the screw 192. The first event of this counterclockwise movement of the yoke is withdrawal of the segment 208 from the gear 180. Immediately after withdrawal is complete the back of the segment 208 engages the stop 210 so that the further movement of the yoke on the pin 198 produces a change in the angular relationship of the lever 206 to the arm 202, the back of the segment sliding along the stop 210. Finally there is attained the position illustrated in Figure 8.

In the above described operation, the finally

attained position of the parts illustrated in Figure 8, i. e., with the stop screw 210 engaging the frame, so locates the segment 208 that in its operation, as described above, it will advance the trick wheel through two steps by reason of its engagement with the gear 180 two teeth behind the location of previous engagements. In order that a particular succession of single and double steps may be imparted to the trick wheel to result in its complete rotation during the occurrence of various numbers of courses of knitting, provision is made to insure either single or double steps under the control of butts carried by the patterning elements of the trick wheel. Additionally, controls are provided to interrupt the advance of the trick wheel during the formations of heels and also for the timing of the trick wheel to bring it to an initial position during the toe formation and during the knitting of the loopers rounds. For the purpose of such controls, the following mechanisms are provided:

A third arm 216 of the lever 186 has pivoted to it at 218 a member 220 which is held in fixed adjustable relationship with the lever 216 by an adjusting screw 222 and a binding screw 224. This member 220 is provided with an upstanding lug 226 which is arranged to move in a slot 228 in a lever 234 pivoted to the frame at 236. The slot 228 has a pair of shoulders 230 and 232 as illustrated. When the lever 234 is in the position illustrated in Figure 9, the lug 226 is unimpeded in its movements, and, accordingly, complete oscillation of the lever 186 may occur, as described above, to give double step advances to the trick wheel. A Bowden wire 238 is connected to one arm of the lever 234 and is actuated through a plunger following cams on the main cam drum of the machine in a fashion similar to that described in connection with the previous modification. A spring 240 normally urges the lever 234 in a clockwise direction to cause a pin 241, carried thereby, to ride on a circular edge 243 of the gear 180 which edge is interrupted by a notch 245.

A lever 242 pivoted on the pin 236 and urged in a clockwise direction by a spring 246 is provided with a hook 244 and with an adjustable screw 248 threaded in an upstanding ear 249, which screw is arranged to be engaged by a downwardly extending portion 250 of the lowermost slide 160, which, though adapted to be acted upon by the lowermost butts on the trick wheel, does not carry a cam portion 162 to act upon the sawtooth butts of the jacks 142.

The control of this lowermost slide by trick wheel butts provides for the positioning of the hook 244 in either of two alternative positions, either clearing the lug 226 as illustrated in Figure 9 or in the path of this lug to prevent the complete return of the lever 186 as it is released by the cam 182. When the hook 244 is in position to engage the lug 226, the gear segment 208 is not withdrawn sufficiently to engage two teeth behind the teeth previously engaged, but is withdrawn only sufficiently to cause it, on the next stroke, to engage one tooth behind those previously engaged. Consequently, under these conditions, the trick wheel will be advanced only a single step in each operation.

The Bowden wire 238 is normally positioned by a cam, corresponding to cam 78 of Figure 7, on the main cam drum so that the pin 241 which it carries cannot drop inwardly of the edge 243. When the machine starts knitting a heel, a higher cam, corresponding to cam 12 of Figure 7, pulls the Bowden wire to bring the stop 230 in the path

of the lug 226. This stop catches the lug on its reverse stroke and prevents clockwise movement of the lever 186. Consequently, the stepping of the trick wheel is interrupted until the lever 234 is permitted to return to the position indicated in Figure 9.

During the knitting of the toe, the Bowden wire 238 is completely released, corresponding to dropping off the cam 74 in Figure 7, so that the lever 234 would be free to move clockwise under the action of spring 240 if it were not for engagement of the pin 241 with the circular edge 243. This edge however, maintains the lever 234 in the condition illustrated so that trick wheel advance continues, the cam 182 being double ended so as to effect advance of the trick wheel during reciprocation. However, as soon as the notch 245 reaches the position of the pin 241, the pin may drop therein with the result that the shoulder 232 may engage the lug 226 and again the oscillations of the lever 186 are prevented. Accordingly, the trick wheel stops. While the retiming of the trick wheel may occur at any time prior to the resumption of active operation of the trick wheel, the retiming during the toe is generally desirable. When, in the formation of the next stocking, patterning is to be resumed under control of the trick wheel, a cam on the main cam drum, corresponding to cam 70 of Figure 7, pulls the Bowden wire 238 to lift the pin 241 out of the notch 245 thereby restoring the lever 234 to an inactive position so that single or double step advances of the trick wheel may be resumed as determined by the position of the lever 242.

It will be evident from the foregoing that both modifications of the invention described herein have in common the characteristic of preventing the return of an advancing member which is cam operated in one direction and yieldingly operated by a spring in the opposite direction to position it for the next operation by the cam. Common also to the two modifications are the fundamental aspects of interruption of advance of a pattern mechanism during the formation of a heel and retiming of the pattern mechanism upon the completion of patterning in one stocking preparatory to the beginning of patterning in the next stocking.

What I claim and desire to protect by Letters Patent is:

1. In a knitting machine, independently movable elements, a cyclically operating pattern device for controlling said elements, means including a periodically movable element for the step-by-step advance of said pattern device, means for positively moving the last mentioned element in one direction periodically, yielding return means for the last mentioned element, and a member movable to a plurality of alternative positions in which it is located in the path of said periodically movable element to prevent its return and so interrupt advance of said pattern device.

2. In a knitting machine, independently movable elements, a cyclically operating pattern device for controlling said elements, means including a periodically movable element for the step-by-step advance of said pattern device, means for positively moving the last mentioned element in one direction periodically, yielding return means for the last mentioned element, a member movable to a plurality of alternative positions in which it is located in the path of said periodically

movable element to prevent its return and so interrupt advance of said pattern device, and means, including a pattern means other than said pattern device for controlling movement of said member to one of said alternative positions.

3. In a knitting machine, independently movable elements, a cyclically operating pattern device for controlling said elements, means including a periodically movable element for the step-by-step advance of said pattern device, means for positively moving the last mentioned element in one direction periodically, yielding return means for the last mentioned element, a member movable to a plurality of alternative positions in which it is located in the path of said periodically movable element to prevent its return and so interrupt advance of said pattern device, and means moving with said pattern device for controlling movement of said member to one of said alternative positions to interrupt advance of said pattern device when the pattern device reaches a predetermined position.

4. In a knitting machine, independently movable elements, a cyclically operating pattern device for controlling said elements, means including a periodically movable element for the step-by-step advance of said pattern device, means for positively moving the last mentioned element in one direction periodically, yielding return means for the last mentioned element, a member movable to a plurality of alternative positions in which it is located in the path of said periodically movable element to prevent its return and so interrupt advance of said pattern device, means, including a pattern means other than said pattern device, for controlling movement of said member to one of said alternative positions, and means moving with said pattern device for controlling movement of said member to another of said alternative positions to interrupt advance of said pattern device when the pattern device reaches a predetermined position.

5. In a knitting machine, independently movable elements, a cyclically operating pattern device for controlling said elements, means including a periodically movable element for the step-by-step advance of said pattern device, means for positively moving the last mentioned element in one direction periodically, yielding return means for the last mentioned element, a member movable to a plurality of alternative positions in which it is located in the path of said periodically movable element to prevent its return and so interrupt advance of said pattern device, means, including a pattern means other than said pattern device, for controlling movement of said member to one of said alternative positions, and means jointly controlled by said pattern means and said pattern device for controlling movement of said member to another of said alternative positions to interrupt advance of said pattern device when the pattern device reaches a predetermined position.

PAUL W. BRISTOW.
